United States Patent

Des. 237,519
Patented Nov. 4, 1975

237,519

CHILD'S RIDING VEHICLE

George W. Ptaszek, East Ave., Pascoag, R.I. 02859

Filed June 10, 1974, Ser. No. 478,085

Term of patent 14 years

Int. Cl. D21—01

U.S. Cl. D34—15 AJ

FIG. 1

FIG. 2

FIG. 3

FIG. 4

FIG. 5

FIG. 1 is a side elevational view of a child's riding vehicle showing my new design;

FIG. 2 is a top plan view thereof;

FIG. 3 is a front elevational view thereof;

FIG. 4 is a rear elevational view thereof; and

FIG. 5 is a bottom plan view thereof.

I claim:

The ornamental design for a child's riding vehicle, substantially as shown.
